UNITED STATES PATENT OFFICE.

JOHN P. SIEGFRIED, OF TOLEDO, OHIO.

COMBINED PUNCHING AND FORGING MACHINE.

SPECIFICATION forming part of Letters Patent No. 292,262, dated January 22, 1884.

Application filed July 3, 1883. (No model.)

To all whom it may concern:

Be it known that I, JOHN P. SIEGFRIED, of Toledo, in the county of Lucas and State of Ohio, have invented certain new and useful 5 Improvements in Combined Punching and Forging Machines; and I do hereby declare the following to be a full, clear, and exact description of the invention, such as will enable others skilled in the art to which it pertains 10 to make and use the same.

My invention relates to improvements in a combined punching and forging machine; and it consists in certain features of construction and in the combination of parts hereinafter described, and pointed out in the claims. 15

In manufacturing various tools it is necessary to punch a hole in some portion of the metal and to form a thimble around the hole on one side of the metal plate adapted to receive and support a handle. Hoes of the kind shown in the drawings and picks may be cited as familiar examples. The thickness of the plate where the hole is to be punched should be such that the surplus metal had in making 25 the hole will, if properly treated, form the said thimble, and at the same time remain integral with the plate.

In the drawings, Figure 1 is a side elevation, and Fig. 2 a front elevation, of my new machine. Fig. 3 is a vertical section, and Fig. 4 a plan view in detail. Fig. 5 is a view in perspective of a variety of hoes that may be punched on the machine.

A represents a supporting frame, to which 35 is attached the anvil A', that supports the punch a. To the upper portion of this frame is journaled the double-crank shaft B, having, however, but a single throw—that is, the cranks throw in unison. Connected with this part of 40 the device are gears, counter-shaft, driving-pulley, clutch, and whatever may be necessary in transmitting power to the machine and regulating the motion thereof. These cranks are provided with the pitmen C, that are connected with and reciprocate vertically the die D, that embraces and is guided by the slide E.

Attached to the shaft B is the bevel-gear b, engaging the gear f, attached to the shaft F by a feather and groove or other suitable means, 50 so that the shaft may reciprocate (simultaneously with the die D, to which it is attached)

through the gear f and the contiguous box. The shaft F is journaled in the box f' and in the bail d, and is held endwise by collars attached to the shaft on either side of the said 55 bail, so that the shaft always retains its relative position vertically to the die D. The lower end of the shaft F is made broad, and is chambered for receiving the hammers G, that are pivotally attached, as shown in Fig. 3. 60 The upper ends or arms of these hammers are forced apart by the strong springs g, and are also actuated as they revolve by the inclines d', Fig. 4, that press the handles toward each other. It will be seen that if a piece of metal 65 be extended through the orifice D' and between the hammers G, and at the same time the shaft F is revolved, the hammers G, by means of the respective arms coming in contact with the inclines d', will first be opened or thrown 70 apart, and as the said arms leave the points of their respective engaging-cams the springs g will cause the hammers to strike both sides of the intervening metal simultaneously, and these two blows will be repeated four times 75 during each revolution of the shaft F. Of course a greater number of inclines could be used, if necessary; also, the gear b might be increased and the gear f decreased in size, so that any desired number of strokes of the 80 hammers may be had during one reciprocation of the die D.

The operation of my device is as follows: While the die D is raised, the piece of metal that it is to be operated upon, properly heated, 85 is placed in the required position on the punch a and the machine set in motion. The descending die forces the piece of metal down upon the punch a, causing the punch first to force a portion of the metal through the hole 90 in the die, but without disengaging this portion of the metal from the balance of the piece. Next, the punch pierces this part of the metal, leaving the punctured part turned upward and around the punch. In the meantime the 95 hammers G have been giving swift and vigorous blows on the metal that is forced up around the punch, forming it into a thimble. The inner part of this thimble of course conforms to the shape of the punch, while the 100 outside of the thimble will be found to be more tapering than the inside and thinner at

the upper edge, having received more blows than the lower part of the thimble.

What I claim is—

1. In a combined punching and forging machine, the combination, with a punch and a reciprocating die, of forging mechanism contained within the die, and adapted to forge the surplus metal taken from the opening formed by the punch and die into a thimble around the said opening and integral with the plate, substantially as set forth.
2. The combination, with the reciprocating die D, of the inclosed forging mechanism, substantially as and for the purpose set forth.

3. The hammers G, the springs g, and the inclines d', in combination with the revolving and reciprocating shaft F, substantially as shown and described.

In testimony whereof I sign this specification, in the presence of two witnesses, this 26th day of June, 1883.

JOHN P. SIEGFRIED.

Witnesses:

JOSEPH W. POST,
FRED A. ALLEN.
